Patented Apr. 8, 1958

182,476

DISPENSER FOR THERAPEUTIC LIQUID

William H. Misson, Los Altos, Calif., assignor to Onox,
Inc., San Francisco, Calif., a corporation of California

Application June 24, 1957, Serial No. 46,690

Term of patent 14 years

(Cl. D83—1)

I claim:

The ornamental design for a dispenser for therapeutic liquid, as shown.
